UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS AND APPARATUS FOR TREATING OIL.

Application filed October 6, 1920. Serial No. 415,140.

This invention relates to a process and apparatus for treating oil and refers more particularly to a process in which, as part of a continuous operation, the oil may be subjected to different temperatures and pressures in a series or battery of stills and the reflux condensate continuously returned to a succeeding still of the battery so as to be subjected to different cracking conditions than in the still in which it was originally treated.

In the drawing, the single figure is a view, in side elevation of my improved apparatus for carrying out the process.

Referring specifically to the drawing, 1 designates a furnace in which are mounted a plurality of stills 2, 3, 4 and 5 of any suitable type, those in the drawing being shown as of the shell type, although coils may be used. Oil is fed to the first still 2 of the battery through feed line 6 having throttle valve 7 connected to charging pump 8, leading to any suitable source of raw oil supply. The stills are connected by the liquid overflow lines 9, 10 and 11, as shown and are provided with suitable residue drawoffs 12, controlled by suitable throttle valves (not shown). The stills are provided with suitable vapor outlet pipes 13, 14, 15 and 16 in which are respectively inserted throttle valves 17, 18, 19 and 20. The pipes 13, 14 and 15 project into the lower ends of reflux condensers or dephlegmators 21, 22 and 23 respectively and are provided with spaced cap members 24, the arrangement being such that the vapors can freely pass into the reflux condensers but the reflux condensate cannot fall back into the vapor pipes. The pipe 16 on the still 5 leads to a similar dephlegmator 25 which is provided with the drawoff pipe 26, having throttle valve 27. The upper ends of each of the dephlegmators are connected by branches 28 to a manifold vapor line 29. Throttle valves 30 are interposed in the lines 28. The manifold line 29 leads to condenser coil 31 seated in condenser box 32. The lower end of this coil is connected by pipe 33, having throttle valve 34 to the upper end of a receiver 35. This receiver 35 is provided with pressure gauge 36, liquid level gauge 37, gas outlet pipe 38, having throttle valve 39 and liquid drawoff pipe 40, having throttle valve 41.

The reflux condensate from each reflux condenser is returned to the next still of the

series by means of return pipes 42, preferably provided with vapor traps 43. In each of these pipes 42 is interposed a pump 44, provided with valves 45 and 46 on either side of the pump. Beyond these valves so as to by-pass the pump is a by-pass line 47 provided with throttle valve 48. Suitable throttle valves 49, 50 and 51 are interposed in the liquid transfer lines 9, 10 and 11 respectively.

The process may be operated as follows: Fuel oil, as for example, Mexican or California fuel oil or crude, may be intermittently or continuously fed into the still 2 and there subjected to a pressure of 300 pounds and to an oil temperature of 650 degs. F. The oil in the still 3 may be subjected to a pressure of 250 pounds and a temperature of 650 degs. F. The oil in the still 4 is subjected to a pressure of 200 pounds and a temperature of 700 degs. F. The oil in the still 5 may be subjected to a pressure of 150 pounds and a temperature of 750 degs. F. The dephlegmators may be subjected to a pressure of say, 150 pounds, and the manifold line 29 subjected to the same pressure while the condenser coil 31 is subjected to a pressure of 100 pounds and the receiver to a pressure of 75 pounds. This may be accomplished by suitably regulating the valves 17, 18, 19 and 20 and 49, 50 and 51 for the still pressures and by opening the valves 30 and regulating a valve 30' in the manifold line for the pressure on the dephlegmator and by regulating the valves 34 for the pressure on the condenser coil and the valves on the receiver for pressure thereon. In this case, although the pressure on the stills successively decreases, the pumps must be used as the dephlegmators are under lower pressure. The condensate in the last reflux condenser 25 may be permitted to fall back into the still 5 or drawn off through the line 26, the valve 27 being suitably regulated to maintain the desired pressure.

As a modified manner of carrying out this process, a pressure of 200 pounds and a temperature of say, 600 degs. F. may be maintained on the still 2, a pressure of 250 pounds and a temperature of 700 degs. F. maintained on the still 3; a pressure of 300 pounds and a temperature of 800 degs. F. maintained on the still 4; and a pressure of 325 pounds and a temperature of 900 degs. F.

degs. F. maintained on the still 5. The dephlegmators may all be maintained at 150 pounds pressure and the condenser coil and receiver at the same pressure, by suitably regulating the valves. In this case, it will be necessary to use the pumps 44 inasmuch as the reflux condensate must be pumped to a still of higher pressure than the dephlegmator.

10 As to other modified methods of carrying out the process, I may use either the first method described or the second method and maintain each dephlegmator under the same pressure as the still to which it is connected. In such cases, the pumps 44 need not be used where the stills are at successively decreasing pressures but will have to be used where the stills are at successively increasing pressures. As a still further 15 modification of the process, any one of the four methods above described may be used except that the temperatures instead of increasing through each still, will decrease, as for example, starting at the first still with 20 a temperature of 800 degs. and dropping 50 degs. in each successive still.

From the foregoing, it will be seen that wide variations and in fact, different processes may be carried out in this one apparatus.

30 I claim as my invention:

1. In an apparatus for cracking petroleum oil, the combination with a series of inter-connected stills, of a reflux condenser connected to each still, connections for returning reflux condensate produced from vapors from one still to a succeeding still of the series, means for maintaining pressures on the stills, means for maintaining different pressures on the dephlegmators, pumps interposed in the said connections, and means for bypassing any of said pumps.

2. In an apparatus for cracking petroleum oil, the combination with a series of inter-connected stills, means for introducing oil to one of the stills to be successively fed to the other stills, of a reflux condenser connected to each still, connections for returning reflux condensate from one condenser to a succeeding still of the series, means for maintaining pressures on the stills, pumps interposed in the said connections, and means for bypassing any of said pumps.

3. A process for cracking hydrocarbon oil under the pressure of self generated vapors which consists in maintaining successive bodies of oil under successively higher temperatures in separated zones, in taking off vapors from each zone and separately subjecting them to reflux condensation, in passing the reflux condensate obtained from the vapors taken off from a zone of lower temperature to the zone of next succeeding higher temperature without permitting such condensate to return to the zone in which

the vapors from which it were condensed were generated.

4. A process for cracking hydrocarbon oil under a self generated vapor pressure consisting in maintaining the oil undergoing treatment in a plurality of successive bodies under successively higher temperature conditions, in passing vapors generated from each of said bodies to an independent dephlegmator wherein reflux condensation occurs, in passing reflux condensate from each of said dephlegmators, except the dephlegmator to which the vapors generated from the body of oil maintained at the highest temperature are passed, directly to the body of oil maintained at the next successively higher temperature than the temperature at which the oil, from which the vapors producing the reflux condensate are released, is maintained.

5. A process for cracking hydrocarbon oil under a self generated vapor pressure consisting in subjecting the oil to successively higher temperatures in a plurality of successive heating zones, in taking off vapors evolved from the oil heated in each zone prior to the passage of the oil to the next heating zone, and in subjecting such vapors to separate reflux condensation and in passing the reflux condensate separated from the vapors taken off from the oil heated in each of said heating zones, except the last, to the next succeeding heating zone, without permitting any of the reflux condensate to return to that heating zone in which the oil, giving up the vapors from which the condensate is condensed, is being heated.

6. A process for cracking petroleum oil consisting in distilling the oil at a predetermined cracking temperature in a heating chamber, taking off vapors therefrom and subjecting them to reflux condensing action, passing the unvaporized portion of the oil to a second heating chamber where it is subjected to a higher temperature, directly delivering said reflux condensates to the second heating chamber for further treatment, subjecting the vapors from the second chamber to reflux condensing action, and likewise directly delivering the condensate and the unvaporized portion of the oil from the second chamber to the third chamber for treatment at a still higher temperature, and maintaining a uniform super-atmospheric pressure on the oil under treatment.

7. A process for cracking petroleum oil consisting in distilling the oil at a predetermined cracking temperature in a heating chamber, taking off vapors therefrom and subjecting them to reflux condensing action, passing the unvaporized portion of the oil to a second heating chamber where it is subjected to a higher temperature, directly delivering said reflux condensates produced from vapors discharging from the first men-

tioned chamber to the second chamber for further treatment, subjecting the vapors from the second chamber to reflux condensing action, and likewise delivering the reflux condensate and the unvaporized portion of the oil from the second chamber to the third chamber for treatment at a still higher temperature.

8. A process of cracking petroleum oil,

comprising introducing oil to a still, a portion of said oil being passed to succeeding stills, in progressively increasing the temperatures of the successive stills, in independently discharging vapors from each still to a reflux condenser, in passing reflux condensates produced in one still directly to a succeeding still of a higher temperature.
